UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

FURNACE FOR HEATING METAL BILLETS OR INGOTS.

1,121,621.

Specification of Letters Patent. Patented Dec. 22, 1914.

Application filed November 22, 1913. Serial No. 802,500.

To all whom it may concern:

Be it known that I, JEROME R. GEORGE, a citizen of the United States, residing at Worcester, in the county of Worcester and 5 Commonwealth of Massachusetts, have invented a new and useful Improvement in Furnaces for Heating Metal Billets or Ingots, of which the following, together with the accompanying drawing, is a specification.

10 My invention relates to furnaces for heating metal billets or ingots preparatory to their being rolled and drawn into rods, wire, or other desired forms.

15 One object of the invention is to provide a billet heating furnace so constructed that the cinder, slag and molten metal which drop from the highly heated billets may be conveniently removed from the furnace 20 while the furnace is in operation.

25 Another object of the invention is to construct a billet heating furnace so that the highly heated products of combustion will be brought into contact with the billets within the furnace in such manner that the greatest heating efficiency of the fuel may be attained.

30 Other objects and advantages will appear from the following description taken in connection with the accompanying drawing which shows a vertical longitudinal section of one form of furnace constructed in accordance with my invention.

35 The furnace shown in the drawing includes a casing 1 having a floor 2, the space 3 above the floor constituting the billet heating chamber. The wall 4 at the charging end of the furnace has an opening 5 through which the billets 6 are introduced into the

40 heating chamber 3 by means of the hydraulic ram 7. The opening 5 is normally closed by an inwardly swinging door 8. A longitudinal track 9 composed of a series of water cooled pipes is carried above the floor 2 by

45 a series of supports 10, the track extending from the hydraulic ram 7 through the opening 5 and along the heating chamber 3 to the point at which the heated billets are removed from the furnace. As the billets 50 are fed into the furnace through the opening 5, two or more U-shaped separators 11

are dropped over every alternate billet to keep the billets separated and prevent their adhering to each other after they have become highly heated at the discharge end of 55 the furnace.

A discharge opening 12 is provided in the side wall of the furnace at the inner end of the track 9 and a transverse track 13, which may be water cooled, is located in line 60 with this opening. The main portion of the track 9 is slightly above the transverse track 13, but its inner or discharge end dips below the track 13 and then rises vertically at its opposite side to form a stop 14. The billets 65 are fed into the furnace sidewise in a continuous series and when the foremost billet reaches the inner end of the main horizontal portion of the track 9, it drops over onto the transverse track 13 as shown in the drawing, 70 whence it is withdrawn from the furnace by means of tongs or pushed out of the furnace through the discharge opening 12 by means of a ram or other agency acting through another opening in the opposite wall of the 75 furnace. The stop 14 prevents billets from falling over the side of the transverse track 13 onto the bottom of the furnace. A series of openings 15 in the side wall of the furnace and opposite the path of the billets as 80 they are forced along the track 9 permit inspection of the billets and the insertion of pokers or tongs for the purpose of replacing them in proper position if they become displaced for any reason. The openings 15 85 nearest the discharge end of the furnace are sufficiently large to permit a billet to be withdrawn if it becomes overheated, or if it is desired to withdraw it for any other reason. 90

The furnace is extended beyond the inner end of the track 9 and the discharge opening 12 to inclose the mixing and combustion chamber 16 which is supplied with gaseous fuel through the downwardly directed passageway 17 and with air through the downwardly directed passageway 18. The bottom or floor 19 of the mixing and combustion chamber 16 is inclined downwardly from its outer end so that its inner end is 95 100 somewhat below the track 9 and the path of the billets supported thereon. The inner or

forward end 20 of the floor 2 is inclined downwardly toward the front of the furnace so that the forward end of the inclined portion lies somewhat below the inner or rear end of the floor 19 of the combustion chamber, thus forming an opening 21 at the forward end of the floor 2. The opening 21 is normally closed by a swinging door 22. This inclination of the forward end of the floor 2 also causes a substantial enlargement of that portion of the heating chamber which lies under the forward end of the track 9.

In the operation of the furnace the billets are removed slowly in a continuous series from the opening 5 to a point opposite the discharge opening 12. The gaseous fuel and air entering through the passageways 17 and 18 are mixed and a large part of the combustion takes place in the chamber 16, the inclined floor 19 conducting a large proportion of the heated gases to the enlarged space between the inclined end 20 of the floor 2 and the layer of billets above. The heated gases then pass along the heating chamber 3 to the rear of the furnace where they pass downwardly through the passageway 23 and thence through the opening 24, the chamber 25, the opening 26 and the passageway 27 on the way to the stack. The chamber 25 may be used, if desired, for heating bricks to be used later for heating gaseous fuel for the same or other furnaces. As the billets move toward the discharge opening 12 they become more and more heated until finally their temperature is so great that cinder, slag and molten metal drop from them upon the floor 2 below. The floor 2 is so designed that when the furnace is running normally the cinder, slag and molten metal begin to drop just forward of the upper or rear extremity of the inclined portion 20 of the floor 2. When there is sufficient accumulation upon the inclined portion of the floor 2 to interfere with the proper operation of the furnace, it may be raked forwardly through the opening 21, this opening being located conveniently for this purpose. The inclined portion 20 of the floor 2 also acts to deflect the heated gases against the lower surface of the series of ingots, the heating effect being obviously greater than if the gases were to pass principally above the billets. The inclination of the portion 20 of the floor 2 causes the molten metal which drips from the highly heated billets to flow by gravity through the opening 21 to a point in front of the furnace whence it may be conveniently removed. This is an important feature in the operation of the furnace, for if the molten metal which drips from the billets does not leave the furnace immediately, it has a very injurious effect upon the furnace lining with which it comes in

contact, necessitating frequent repairs and renewals of the lining. In the described construction, too, the molten metal is deposited in front of the furnace and therefore at the point whence it may be most conveniently removed.

While I have shown and described the details of one form of my invention, I do not wish to be limited to such details as changes may be made without departing from the spirit of the invention; but

Having described my invention, what I claim as new and desire to secure by Letters Patent is:

1. In a billet heating furnace, a longitudinal track having a substantially horizontal portion to support highly heated billets, and a floor beneath the track, the floor having a downwardly and forwardly inclined portion under said horizontal portion of the track to receive molten metal dropping from the highly heated billets, there being an opening through the front wall of the furnace at the forward end of the inclined portion of the floor to permit the molten metal to be deposited by gravity in front of the furnace.

2. In a billet heating furnace, a longitudinal track for the billets, a floor beneath the track, the furnace being extended forwardly beyond the track to inclose a combustion chamber, the bottom of the combustion chamber extending rearwardly to a point between the forward ends of the track and floor to conduct the heated gases to the space beneath the track, and the space between the rear end of the bottom of the combustion chamber and the forward end of the floor being left open to permit removal of accumulations on the floor.

3. In a billet heating furnace, a longitudinal track for the billets, a floor beneath the track with its forward end inclined downwardly, the furnace being extended forwardly beyond the track to inclose a combustion chamber, the bottom of the combustion chamber extending rearwardly to a point between the forward ends of the track and floor to conduct heated gases to the space beneath the track, and the space between the rear end of the bottom of the combustion chamber and the forward end of the floor being left open to permit removal of accumulations on the floor.

4. In a billet heating furnace, a longitudinal track for the billets, a floor beneath the track, the furnace being extended forwardly beyond the track to inclose a combustion chamber, the bottom of the combustion chamber extending downwardly and rearwardly to a point between the forward ends of the track and floor to conduct heated gases to the space beneath the track, and the space between the rear end of the bottom of the combustion chamber and the forward end of the floor

end of the floor being left open to permit removal of accumulations on the floor.

5. In a billet heating furnace, a casing enclosing a space constituting a billet heating chamber at one end and a combustion chamber at the other end, the floors of said chambers being separated to provide a cleaning opening and the end of the floor of the heat-

ing chamber nearest the opening being inclined downwardly toward the opening.

Dated this 19th day of November 1913.

JEROME R. GEORGE.
